ELECTRICAL HOROLOGY

Application filed December 21, 1928. Serial No. 327,581.

This invention relates to electrical horology.

It is among the objects of the present invention to provide a novel and improved clock which is adapted to be automatically wound at predetermined intervals of time through electrical means.

A further object of the present invention is to provide in combination with a clock train, a solenoid for effecting a torque on the coil spring for driving the train.

A further object of the present invention is to provide in combination with a clock train, a solenoid, and means for periodically energizing said solenoid to effect a spring to drive the train, said solenoid being operable, through a novel circuit make and break device associated with the train, for predetermined periodical energization.

With these and other objects of the present invention in view, reference may be had to the accompanying drawings, in which

Figure 1 is a rear elevation of a clock embodying one form of my present invention; Fig. 2 is a detail elevation of a driving structure shown in Fig. 1, and

Fig. 3 is a sectional view taken on the line 3-3 of Fig. 2.

Referring more particularly to the drawings, there is by way of illustration shown a suitable clock frame 10, within which the usual clock train including the master gear 11, spring 12 and escapement 13, is mounted, suitably supported by the conventional frame 14.

It will be understood that the present invention is confined to the driving mechanism and that it may be applied to various forms of watches, and clocks, which are not of the general type herein illustrated.

The invention is particularly adapted for use in connection with clocks on motor vehicles, in which it is desired to automatically energize the clock train without the necessity of periodic winding. Associated with the main gear 11, a driving gear 15 is provided, mounted for rotation with an axle 16, the lower end of which is journaled in the lower plate 14, while the upper end is journaled in an arm 17 associated with the upper

plate 14. For urging revolution of the gear 15 to drive the master gear 11, a spirally coiled spring 18 is provided, its inner end being received through an aperture in the gear 15 and thus fixed thereto, while its upper end is fixed to a ratchet wheel 19 which is freely rotatable about the axle 16. Cooperative with the ratchet wheel 19, is a pawl 21 which is mounted upon the extremity of an armature 22 associated with a solenoid 23. The pawl 21 is preferably pivotally mounted in a bifurcated portion of the armature 22, and a spring 24 is provided for normally urging the pawl 21 against the teeth of the ratchet wheel 19. The arrangement is such that upon energization of the solenoid 23, the armature is drawn inwardly, so that the pawl 21 engages one of the teeth of the ratchet wheel 19 and moves it through a fraction of a revolution, whereby the spring 18 is brought under tension so as to urge rotation upon the gear 15. Reverse rotation of the ratchet wheel 19, is prevented by a yieldable stop tongue 25 mounted as at 26. The tongue 25 is preferably of semi-flexible material, its extremity being adapted to engage one of the teeth of the ratchet wheel 19 to prevent reverse rotation thereof.

For controlling the energization of the solenoid 23, a wheel 27 is provided, which is loosely mounted upon the extremity of the hub sleeve 20 of the ratchet wheel 19, its periphery being provided with spaced contact teeth 28 which are adapted to intermittently engage with a yieldable conducting finger 29, the latter being insulated from the casing 10 and being connected through a conductor 30, as shown in Fig. 2, with the windings of the solenoid. The electrical circuit is completed through a battery 31 and conductor 32, which is grounded to the casing 10, whereby the electrical current passes through the wheel 27 and its contact teeth 28.

Operative rotation of the wheel 27, to carry the contact teeth 28 thereof into and out of circuit closing engagement with the conducting fingers 29, is produced through the agency of alternating drive devices, one of which is actuated by the spring driven axle 16, whereby the wheel 27 is moved to 100

carry a contact tooth 28 into circuit engagement with the finger 29, and the other of which is actuated by the ratchet wheel 19, whereby the wheel 27 is moved to carry an engaging contact tooth 28 out of circuit closing contact with the finger 29. The first of these drive devices comprises an arm 38 fixed to and rotated with the axle 16 so as to engage a driven pin 37 which projects from the wheel 27, and the other drive device comprises a slot 34 with which said wheel 27 is provided and into which operatively projects a drive pin 33 carried by said ratchet wheel 19.

In the operation of the mechanism, while the spring 18 is under tension and driving the gear 15, the contact finger 29 is in spaced or separated relation to the adjacent projecting contact teeth 28 of the wheel 27. As the gear 15 turns, turning with it the axle 16, the arm 38 is moved whereby the trailing side of its bifurcated extremity engages the pin 37, thereby advancing the wheel 27 so that a contact tooth 28 is brought into circuit closing engagement with the finger 29, at which time electrical energy is transmitted through the thus closed electrical circuit to the solenoid to energize the same. The circuit closing movement of the wheel 27 takes place while the ratchet wheel 19 and its drive pin 33 remain stationary, the slot 34 in said wheel 27 allowing play for the initial circuit closing movement of the latter relative to said stationary drive pin 33. When the circuit is closed in the manner described, energization of the solenoid swings forward the armature 22, thereby carrying the pawl 21 into advancing relation to the ratchet wheel 19. The rotative movement thus imparted to the ratchet wheel 19 again winds the spring 18 to restore its expended tensional torque. As the ratchet wheel 19 advances, the drive pin 33 is first advanced to abut the forward end of the slot 34 in the wheel 27, whereby the completion of the advancing movement of the ratchet wheel 19 will likewise impart a second advancing movement to the wheel 27 which operates to move the finger engaging contact tooth beyond and clear of the finger 29, so that the solenoid circuit is interrupted and the solenoid deenergized on completion of the spring winding movement of the ratchet wheel. The circuit breaking advance of the wheel 27 moves the driven pin 37 beyond the arm 38, so that the spring driven movement of the clock-train is freely exercised until during such movement said arm 38 again engages and advances the driven pin 37, whereupon the above described operations are repeated and continue thereafter to be successively repeated.

For preventing accidental rotation of the wheels 27, a spring arm 39 is provided, which bears against the face of the wheel in such a manner as to normally retain it against rota-

tion other than that induced by the pins 37 or 33.

From the foregoing it will be readily seen that my invention provides a simple and efficient structure which by the provision of intermittent restoration of the tensional energy of the spring 18, provides for a constant or uninterrupted driving of the clock train.

It will be understood that the structure may be arranged to intermittently energize the solenoid 23 over any desired periods of time, it being preferable to use approximately one-half minute intervals whereby undue tensional relaxation of the spring 18 is avoided, and thus uniform operation may be attained and accurate time keeping maintained by the instrument.

It will also be seen that through the instrument including the finger 29, the device is particularly adapted for use in connection with motor vehicles, the arrangement being such that vibration of the vehicle will not affect the operation of the device and vary the time kept thereby.

What is claimed is:

1. In mechanism of the kind described, a driving gear having an axle rotatable therewith, tensional spring means for transmitting torque to said gear and axle, and means for intermittently restoring expended tension of said spring, said latter means comprising a ratchet wheel connected with the winding end of said spring, an electromagnetic element having a movable armature, a pawl carried by said armature to operatively engage said ratchet wheel, an electric circuit for said element, a circuit make and break means including a rotatable contact means and a stationary contact means, means actuated by said axle for moving said rotatable contact means into circuit closing relation to said stationary contact means, and means actuated by said ratchet wheel for moving said rotatable contact means into circuit breaking relation to said stationary contact means.

2. In mechanism of the kind described, a driving gear having an axle rotatable therewith, tensional spring means for transmitting torque to said gear and axle, and means for intermittently restoring expended tension of said spring, said latter means comprising a ratchet wheel connected with the winding end of said spring, an electro magnetic element having a movable armature, a pawl carried by said armature to operatively engage said ratchet wheel, an electric circuit for said element, a circuit make and break means including a stationary contact finger, and a contact wheel having peripherally projecting contact teeth, means actuated by said axle for advancing said wheel to carry a contact tooth thereof into circuit closing engagement with said contact finger, and means actuated by said ratchet wheel for further

advancing said wheel to disengage said contact tooth from said contact finger.

3. In mechanism of the kind described, a driving gear having an axle rotatable therewith, tensional spring means for transmitting torque to said gear and axle, and means for intermittently restoring expended tension of said spring, said latter means comprising a ratchet wheel connected with the winding end of said spring, an electromagnetic element having a movable armature, a pawl carried by said armature to operatively engage said ratchet wheel, an electric circuit for said element, a circuit make and break means including a stationary contact finger and a contact wheel having peripherally projecting contact teeth, means actuated by said axle for advancing said wheel to carry a contact tooth thereof into circuit closing engagement with said contact finger, means actuated by said ratchet wheel for further advancing said wheel to disengage said contact tooth from said contact finger, and yieldable detent means for retaining said wheel against overthrow.

25 4. In mechanism of the kind described, a driving gear having an axle rotatable therewith, tensional spring means for transmitting torque to said gear and axle, and means for intermittently restoring expended tension of said spring, said latter means comprising a ratchet wheel connected with the winding end of said spring, an electromagnetic element having a movable armature, a pawl carried by said armature to operatively engage said ratchet wheel, an electric circuit for said element, a circuit make and break means including a stationary contact finger and a contact wheel having peripherally projecting contact teeth, said contact wheel having a driven pin, an arm fixed to and rotated by said axle to engage said driven pin to advance said contact wheel to circuit closing position, and a pin and slot connection between said contact wheel and ratchet wheel to advance the former to circuit interrupting position.

50 5. In mechanism of the kind described, a driving gear having an axle rotatable therewith, tensional spring means for transmitting torque to said gear and axle, and means for intermittently restoring expended tension of said spring, said latter means comprising a ratchet wheel connected with the winding end of said spring, an electromagnetic element having a movable armature, a pawl carried by said armature to operatively engage said ratchet wheel, an electric circuit for said element, a circuit make and break means including a stationary contact finger, and a contact wheel having peripherally projecting contact teeth, said contact wheel having a driven pin, an arm fixed to and rotated by said axle to engage said driven pin to advance said contact wheel to circuit closing position, a pin and slot connection between said contact wheel and ratchet wheel to advance the for-

mer to circuit interrupting position, and yieldable detent means for retaining said contact wheel against overthrow.

6. In a power spring winding mechanism, means connected with one end of said spring so as to be actuated by the tensional torque thereof, winding means connected with the opposite end of said spring to restore its expended tensional energy, electro-magnetic means for actuating said winding means, an electric circuit for said latter means including a make and break means, said make and break means comprising a movable contact and a stationary contact, means actuated by said spring driven means, to carry said movable contact into circuit closing relation to said stationary contact, and means actuated by said winding means to carry said movable contact into circuit interrupting relation to said stationary contact.

Signed at Brooklyn, in the county of Kings and State of New York, this 19th day of December A. D. 1928.
